SIGNALING DEVICE

Samuel F. Arbuckle, Highland Park, Mich., assignor to United Lens Corporation, Detroit, Mich., a corporation of Delaware

Application June 18, 1934, Serial No. 731,015

2 Claims. (Cl. 177—327)

This invention relates to a combination illuminating system and particularly to a unitary combination of tail lamp, stop lamp and backing lamp, especially adapted for use with automotive vehicles.

The invention comprehends the provision of a unitary lamp structure capable of energization under various conditions to produce various illuminative qualities for affording visual indications of movement or non-movement of the vehicle as well as directive illumination under certain conditions. The invention further embraces the provision of a unitary lamp structure of this character in combination with the circuit or a system of imparting electrical energy to the lamp filament or filaments operative during a movement of one or more of the vehicle controls.

The invention is all inclusive of a unitary lamp structure embodying a plurality of filaments and a lens and color filter arrangement for indicating a visual indication preferably at the rear of the vehicle of a tail marking light, of a visual stop indication when the vehicle is being brought to a decrease in speed operated through the brake mechanism of the vehicle or other control, and a further illumination controlled by the reversing mechanism of the vehicle or other suitable means for directing sufficient illumination for the roadway to the rear of the vehicle during backing movements thereof.

A further provision of the invention is that of a unitary construction of lamp of this character wherein the entire illuminant producing arrangements are contained within a single housing and wherein through the use of color filter or filters a different character is imparted to the resulting light beams for visibly indicating vehicle movements of non-movements without the use of moving parts or exterior means arranged without the lamp casing.

A further object is the production of a lamp of this character of simplified arrangement embodying few parts, occupying a comparatively small space thus effecting material savings in the production and assembly of the parts.

A further object is the provision of a lamp having a single lens in combination with a color filter; means for producing light beams of different color characteristics for giving various visual indications.

Further objects and advantages are within the scope of this invention such as relate to the arrangement, operation and function of the related elements of the structure, to various details of construction and to combinations of parts, ele-

ments per se, and to economies of manufacture and numerous other features as will be apparent from a consideration of the specification and drawings of a form of the invention, which may be preferred, in which:

Figure 1 illustrates an embodiment of my invention suitably adapted for use at the rear of an automotive vehicle.

Figure 2 is a front view of the device shown in Figure 1 with a portion of the lens removed.

Figure 3 is a somewhat diagrammatic view illustrating the circuits for carrying out the functions of the illuminating system of my invention.

Figure 4 is an isometric view of a color filter and shield forming a part of the invention.

Figure 5 is a detail view illustrating a lens forming a part of the invention.

I have illustrated the arrangement of my invention as utilized for a combination tail lamp, stop lamp and backing lamp for a motor vehicle, but it is to be understood that the invention is not limited to a particular use but is susceptible to variations by incorporation in any arrangement wherever the same may be found to be desirable.

Referring to the drawings in detail and particularly to Figure 1, the lamp structure of my invention comprises a casing 10 preferably of circular configuration and having at its rear portion a flattened face 12 suitable for fixing the lamp to a supporting bracket 13 by means of screws 14 which pass through slots in the bracket 12 and are threaded into openings in an inner reinforcing plate 16, the inner plate 16 being held to the rear flat face 12 of the lamp casing by means of screws 17. The supporting bracket 12 may also be formed or provided with a laterally extending portion 18 serving to hold the license plate or the like.

The forward portion of the lamp is enclosed by a light penetrable wall or closure preferably in the form of a lens 20 having a peripheral flanged portion 21 which sets against a gasket 22 of cork or other suitable material, the latter in turn resting against a metal ring or annulus 23. The lens 20, gasket 22 and ring 23 are secured in place on casing 10 by means of a bezel or annulus 24 having at its upper portion a lug 25 which passes through a slot in the upper portion of the casing 10 to properly position the bezel with respect to the casing as well as to retain the latter in position, the lower portion of the bezel having an extension 26 provided with an opening to receive a retaining screw 27 which passes therethrough into a threaded member 28 suitably se-

cured to the casing 10 so as to provide ample threads for the screw 27. The lens 20 is preferably made of glass or other light penetrable substance having on its rear face a plurality of concentric annular prisms 30 preferably of different intensities in order to direct and reflect light passing therethrough, the lens also being provided on its front face with vertically disposed flutes 31 for laterally spreading light. In a practical embodiment of the lamp, the lens is preferably of an amber color for a purpose to be hereinafter explained.

Positioned adjacent the plate 16 is a member 32 preferably of insulating material and secured 15 to the plate 16 a ring-like member or bracket 33 of conducting material having an upwardly angularly projecting portion 34 which serves as a socket or support for a lamp bulb 35 provided with a filament 36 forming a source of illumination. The member 33 is also formed at its lower portion with an angular projection 38 provided with an opening 40 serving as a socket for supporting the lamp bulb 42 having a filament 43. The projection 38 serves to support one end of 25 a color screen or cover 44 by means of a plurality of threaded members 45. The cover 44 is preferably made of a flexible transparent colored material, in the embodiment illustrated this cover is made of red colored translucent material such 30 as a pyroxylin compound or celluloid. The other end of the cover is in engagement with the inner side of a projection 47, thereby acting as a colored shield enclosing the lamp bulb 42. As particularly shown in Figure 4, the projection 47 forms 35 a part of the light translucent member or lens 50 which may be constructed of glass or other suitable material. Lens 50 is formed with a portion which fits the opening 52 provided in the lower portion of casing 10, and is removably positioned 40 on casing 10 by means of the clamping members 54 and 55 which serve to compress a resilient gasket 53 located between lens flange 57 and casing 10, providing a tight engagement of the parts and forming an efficient sealing means for keeping 45 water and moisture from damaging the parts positioned in said casing. Filament 43 of lamp bulb 42 is used when energized to provide a warning signal as a tail light marker, the filament being of a lesser intensity than filament 36 of lamp bulb 35, filament 36 being used as 50 a stop and backing up signal when energized. The energization of filament 42 also provides means for illuminating the license plates, which as hereinbefore mentioned, may be secured to portion 18 of the supporting bracket 12 by the 55 passage of light through lens 50.

As shown in Figure 1, the rear face 12 of the casing 10 is provided with an opening 60 for accommodating connecting plug 62. The plug 62 is made of a suitable insulating material and is provided with terminal contacts 63 and 64 serving as a circuit connection through means of the leads 66 and 67 to a suitable source of energy as will be hereinafter described. The terminal contacts 63 and 64, which may be in the form of sleeves, are adapted to engageably receive the terminal contacts 69 and 70, insulatingly supported on housing 10. Contacts 69 and 70 are secured to insulating member 32 and are formed at one end with enlarged head portions which 65 are in engagement with the contact members 72 and 73 provided with bent portions adapted to engage the contacts 75 and 76 carried by the base member of the lamp bulbs 35 and 42. The contacts 75 and 76 are respectively connected 70 with one end of filaments 36 and 43 enclosed,

light bulbs 35 and 42, the other end of the filaments being connected to the cylindrical member of current conducting material forming part of the base portion of each of the light bulbs.

The circuits used in connection with the signaling device including certain of the control parts of an automotive vehicle which serve as the means for controlling said circuits are shown in Figure 3. In the embodiment illustrated the source of energy for supplying electric current is 10 shown as a storage battery 80 having one terminal grounded as at 81 by means of the lead 82. The other terminal of battery 80 is connected through means of leads 84 and 85 to a switch blade 86 adapted to engage contact 87 connected by lead 67 to terminal contact sleeve 64 being in engagement with stationary contact 70 one end of which is in contact with the bent portion of arm 73 engaging the contact 76 connected to one end of filament 43 of the light bulb 20 42. The other end of filament 43 is connected to the outer metallic shell carried on the base portion of lamp bulb 42 which in turn is in engagement with bracket 38 grounded as at 79.

The battery is connected by means of leads 84 25 and 88 to a relatively stationary contact 90. Positioned adjacent contact 90 and in suitable spaced relation is a contact 91 both adapted to be engaged by a movable contact 92 insulatingly carried by arm 93. The arm 93 is secured to a portion of the 30 brake pedal 96 and when the latter is moved in the direction indicated by the arrow, movable contact 92 engages the stationary contacts 90 and 91 as shown in dotted lines. Contact 91 is connected with the filament 36 of the light bulb 35 35 by means of leads 95 and 97, hence to lead 66, contact 63 cooperating contact 69, arm 72, in engagement with contact 75 of lamp base 35 hence to one end of filament 36. The other end of filament 36 is grounded as at 37 by bracket 34. 40

The filament 36 of lamp bulb 35 is also connected to the battery 80 through a portion of the circuit used for energizing filament 43 of lamp 45 42 which is controlled by switch blade 86. The circuit of lamp filament 36 including the leads 84 and 85 connected to switch blade 86 is also controlled by a switch operable by the gear shift lever, the rest of the circuit being as follows: From stationary contact 87 by means of lead 99 to a stationary contact 100 which is suitably 50 spaced from another stationary contact 101 both adapted to be engaged by a bridging contact 102 insulatingly carried by an arm 103 actuated by an extension of the gear shift lever 106 projecting through a suitable opening in gear shift housing 55 108. When the gear shift lever 106 is moved in the direction indicated by the arrow to the position shown in dotted lines, movable contact 102 engages the stationary contacts 100 and 101 as shown in dotted lines. Contact 101 is connected to filament 36 of lamp 35 by means of lead 110 connected to lead 97, hence to lead 66, 60 cooperating contacts 63 and 69 hence to contact arm 72 in engagement with contact 75 connected to one end of filament 36, the other end of which is grounded as at 37 by bracket 34. It should be noted that the energization of filament 36 by this circuit can only take place when the gear shift lever is in the position illustrated in dotted lines and when the switch blade 86 is in contact 65 lines and when the switch blade 86 is in contact 70 with terminal 87 which takes place when filament 43 of tail light 42 is energized.

The operation of the device is as follows: the closing of switch blade 86 of the tail lamp switch for night driving, which in the present embodiment 75

ment can be accomplished manually or by other suitable means, energizes filament 43 of lamp 42 by means of current passing from the battery 80 through leads 84, 85, the closed switch, hence 5 through lead 67 to cooperating contacts 64 and 70 connected in turn to arm 73 which is in engagement with contact 76 connected with one end of filament 43 of lamp bulb 42, the return circuit being accomplished through suitable ground connection as particularly shown by the means of bracket 38 grounded as at 79 permitting the return flow of current to the battery 80 through its ground connection 81 and lead 82, connected to the other battery terminal. The flow of current through this circuit causes the energization 10 of the filament 43 producing light rays which in passing through the colored translucent cover 44 produce a colored light which in turn is projected and directed by lens 20. This colored light is used 15 as a warning signal or tail light to indicate during poor visibility such as at night time or during fog the presence of a vehicle to other observers such as approaching drivers. In the present embodiment the colored shade 44 changes 20 the color of the light rays produced by filament 43 to a red or ruby color, however, this colored light is not changed or modified while passing through lens 20 which is of an amber color, the light projected from the device being of a red or ruby color. Light rays from filament 43 passing through lens 50 serve to render visible the license plate supported on extension 18 of lamp supporting bracket 12.

When the operator of the vehicle depresses 35 the brake pedal 96 as indicated by the arrow, movable contact 92 is urged into engagement with stationary contacts 90 and 91, completing the circuit between the battery 80 and filament 36 thereby causing the energization of filament 36 40 of lamp bulb 35. As hereinbefore pointed out, filament 36 is preferably of a greater candle power than filament 43 thereby causing the projection or emission of a strong amber colored light beam through lens 20. In case the filament 43 is in 45 operation and at the same time filament 36 is energized, condition which will take place at night, the light projected from the device through lens 20 is of amber color as the colored light produced by the filament 43 and screen 44 is rendered 50 imperceptible to the observer due to the strong illumination produced by filament 36. The color of the light projected from the signaling device through lens 20 by the energization of filament 36 or by the illumination caused by energization 55 of both filaments 36 and 43 as a stop signal serves to indicate to observers or approaching drivers the slowing or stopping of the vehicle, this projected light being of amber color, distinguishing the same from the tail light or warning signal, which is of red or ruby color.

In order to provide an efficient and clearly distinguishable signal from a comparatively long distance filament 36 is preferably located at the 65 focal point of the concentric prisms of different intensity or refractive power 30, located in the rear face of lens 20, thereby serving to reflect the light rays emitted from filament 36 in the same manner as a parabolic reflector and due to 70 the prisms of flutes 31 in the front face, the light passing through lens 20 is spread, thereby giving lateral illumination adjacent to the signal lamp. When the pedal 96 is released or returned to its normal position, the circuit is broken by disengagement of contact 92 with the relatively sta-

tionary contact 91, thereby disconnecting filament 36 from storage battery 80.

When the operator desires to reverse the movement of the vehicle through the actuation of the gear shift lever 106, moving this lever in the direction indicated by the arrows to the position illustrated in dotted lines, movable contacts 102 engages stationary contacts 100 and 101 and as has been hereinbefore pointed out, and if the switch blade 86 is in contact with its cooperating stationary contact 87, the energization of filament 36 will take place, the circuit being established by moveable contact 102 as follows: From one terminal of battery 80, by leads 84 and 85, to switch blade 86, in engagement with stationary contact 87, hence to lead 99, stationary contact 100 in engagement with movable contact 102, the same also in engagement with stationary contact 101, hence to lead 110, conductor 97 and leads 66, stationary contact 69 contacting 20 arm 72 in engagement with contact 75 of filament 36, the other end of which is connected to ground 37 through its supporting bracket 34, the flow of current being accomplished by the return ground connection to the other terminal of the 25 battery from ground 37 to ground 81 and conductor 82 connected to the other terminal of the battery.

It should be noted that when the sources of lights are energized through the actuation of switch blade 86 and gear shift lever 106 the light projected through lens 20 is of greater intensity than whenever filament 36 is energized by the 30 brake pedal or when filament 43 is energized by the actuation of switch blade 86 due to the fact 35 that under that condition filament 43 of light bulb 42 is energized as well as filament 36 and lamp bulb 35, the summation of the candle power in both filaments serving to project a bright light of strong amber color, enabling the driver to 40 distinguish obstructions or objects in the rear of the vehicle so that the same be avoided by the operator. If switch blade 86 is out of engagement with stationary contact 87 this circuit can 45 not be completed, as the energization of filament 36 by the actuation of the gear shift lever can only be established when the tail light or warning signal is in operation. This arrangement permits that during the day time or when the condition of visibility is satisfactory, the reversal of 50 movement of the vehicle by the actuation of the gear shift lever does not cause the energization of the filament 36 of lamp bulb 35, thereby preventing the consumption of energy from storage battery 80. Whenever the gear shift lever 106 is 55 returned to its normal position or the position indicated in full lines in Figure 3, this movement actuates arm 103 to disengage contact 102 from stationary contacts 100 and 101, thereby 60 breaking the circuit of filament 36 and disconnecting the filament from storage battery 80.

From the foregoing, it will be understood that although the device includes a plurality of light bulbs having preferably filaments of differing candle power within a single casing, the light 65 projected is of different colors and of sufficient contrast to provide different signals such as a tail light or warning signal, and in addition a signal of different character and intensity for indicating movements of the vehicle, including a 70 backing up signal, the arrangement being such that each signal is distinguishable from the other and in no way interferes to give a false impression to approaching observers or vehicle operators.

It is apparent that, within the scope of the invention, modifications and different arrangements may be made other than is herein disclosed, and the present disclosure is illustrative merely, 5 the invention comprehending all variations thereof.

What I claim is:

1. A device of the class described, comprising a housing; a light penetrable wall having a definite color characteristic constituting one part of said housing, said wall having a plurality of concentric prisms of different refractive power having a common focus; two independently usable light sources within said housing, one of 10 said light sources located substantially at the focus of said prismatic wall, a second light source spaced from said first light source; a shield of a different color value than the light penetrable wall interposed between said second light and said 15 wall; said first mentioned colored wall capable of transmitting light emanating through said shield; means to energize the light source at focus to project light through said penetrable wall substantially unaffected by the color of said shield 20 and means to independently energize said second 25 light source to project light through said wall of

different color value than that produced by the first mentioned light source.

2. A device of the class described, comprising a housing; a light penetrable wall having a definite color characteristic constituting one part of 5 said housing, said wall having a plurality of concentric prisms of different refractive power having a common focus; means arranged to spread light passing through said light penetrable wall; two independently usable light sources within 10 said housing, one of said light sources located substantially at the focus of said prismatic wall, a second light source located out of the focus of said prismatic wall; a shield of a different color value than the light penetrable wall interposed 15 between said second light and said wall; said first mentioned colored wall capable of transmitting light emanating through said shield; means to energize the light source at focus to project light through said penetrable wall substantially un- 20 affected by the color of said shield and means to independently energize said second light source to project light through said wall of different color value than that produced by the first men- 25 tioned light source.

SAMUEL F. ARBUCKLE.
